UNITED STATES PATENT OFFICE.

HARRY W. BROWN, OF WINCHESTER, MASSACHUSETTS, ASSIGNOR TO GENERAL ELECTRIC COMPANY, A CORPORATION OF NEW YORK.

CURRENT-LIMITING SWITCH FOR ELECTRIC LIGHTS.

SPECIFICATION forming part of Letters Patent No. 772,921, dated October 25, 1904.

Application filed December 3, 1901. Serial No. 84,541. (No model.)

To all whom it may concern.

Be it known that I, HARRY W. BROWN, a citizen of the United States, residing in Winchester, county of Middlesex, State of Massachusetts, have invented certain new and useful Improvements in Current-Limiting Switches for Electric Lights, of which the following is a specification.

In installing incandescent lamps supply companies frequently wire a consumer's premises and furnish current on a contract basis by which the customer is permitted to burn a certain maximum number of lamps, his house being provided with enough lamps so that he can have sufficient light in any part of the premises. Thus it may be agreed that the consumer is not to burn at any time more than ten lamps at once, although his house may contain in the various rooms thirty or forty lamps. In order to provide a check against dishonesty on the part of the consumer, devices have sometimes been placed on his premises for breaking the circuit or otherwise penalizing the customer in case more than enough current to keep the agreed number of lamps burning is used.

My invention relates to a system of this type, the object being to increase its flexibility and afford the consumer greater convenience. Systems of this type as heretofore proposed involve the extinguishment of the lights in case the prescribed number of lamps are exceeded or some other plan of forcing upon the consumer's notice the fact that he is exceeding the contract limit.

I provide means for opening the switch and cutting in resistance on the lamp-circuit in case the contract number of lamps are exceeded, thus dimming the lights and subjecting the consumer to inconvenience and yet permitting sufficient illumination so that the circuit-controller may be found and the damage corrected. I provide also a prepayment device by which in case a greater than the number of lamps provided for by the contract is desired an unlimited amount of current may be obtained by paying a coin of determinate value through the prepayment device, and after inserting such a coin the consumer

may wind a piece of clockwork housed within a closed casing and close a short circuit around the switching devices, said short circuit being maintained for a prescribed time. Thus in case of an emergency when the consumer stands in strong need of more light he may obtain the same by depositing a coin and operating a control-handle, after which he may use as many lamps as he desires for a definite interval of time—say two or three hours—after which the short-circuiting switch will be automatically thrown and the apparatus restored to its initial condition, all of the lamps being dimmed and the consumer forced either to deposit another coin or turn off the extra lamps.

My invention therefore comprises an automatic switch for dimming the lights on a consumer's premises in case an excessive number of lamps are burned at the same time. It comprises also means for permitting an excessive number to be used for a determinate time upon the payment of a coin or other prescribed act, leaving a record for the supply company.

Other features of novelty will be more specifically hereinafter described and will be definitely indicated in the appended claims.

The claims in the present application are directed to the invention in combination with prepayment devices or other means for governing the lights in some prescribed way, claims for the broader features of the invention being embodied in a divisional application hereof, Serial No. 140,976, filed on or about January 29, 1903.

In the accompanying drawings, Figure 1 is a front view of an apparatus embodying my improvements. Fig. 2 is a diagram showing the circuit arrangements. Fig. 3 is a sectional view. Figs. 4, 5, 6, and 7 are views in detail of various parts.

Referring first to the diagram Fig. 2, 1 represents the lamp-circuit in the consumer's premises, and 2 a solenoid in series relation to the circuit, provided with a movable core carrying a contact 3, normally short-circuiting a resistance 4. Thus if the consumer's contract limits him to the use of five lamps

in case more than this number are used at the same time the solenoid, which is calibrated to lift its core when six or more lamps are burning, opens a short circuit by way of contact 3 and cuts in the resistance 4, thereby dimming the lamps and forcing the consumer's attention to the fact that he is exceeding his rights under the contract. 5 represents an automatic switch, normally open, but which 10 may be closed so as to short-circuit the coil 2 in case a definite prepayment is made, and 6 an auxiliary switch in the same short circuit, the purpose of which will presently appear. Thus by depositing, say, fifty cents within a 15 closed casing provided with a door to which only an employee of the supply company has access, the consumer may operate a handle so as to close the contacts 5 and 6, as indicated in Fig. 2, thereby short-circuiting the solenoid 2 and permitting its core to drop and complete the lamp-circuit independent of the resistance 4, and so long as the contacts are closed the consumer may use all the lamps with which the premises are equipped. These 20 operations may be effected by many types of apparatus. One such type is shown in Figs. 1, 3, 4, 5, 6, and 7, in which 7 represents a closed cast-iron casing provided with a door 8, adapted to be secured by a seal, lock, or 25 other contrivance which will permit access only of an employee of the supply company to the cash-box 9. The closed casing is provided with a coin-chute 10, the lower end of which terminates in a closed rotary section 30 10^a, containing a chute or channel which is large enough to freely admit transit of a fifty-cent piece. This movable section is fastened to the winding-arbor of a clock-train 11, provided with an escapement, so as to mark time. 35 Projecting through the casing is a winding-stem 12, slotted, as indicated in Fig. 7, to admit the coin, and provided on the outside of the casing with a handle 13, playing between two cast lugs on the door of the casing. When 40 the handle is turned against the upper lug, as indicated in Fig. 3, the slot in the stem is in alinement with the chute in the movable section of the coin-duct, assuming that the apparatus is in an unwound condition, as indicated 45 in Fig. 3. If now a fifty-cent piece be dropped into the chute or a coin of other determinate value for which the apparatus is constructed, it will fall until it assumes the position indicated in dotted lines, thereby locking the handle to the movable section of the chute and 50 permitting the consumer to wind the clock-work for a definite range of movement. I prefer to design the parts so that the range of movement permissible to the handle will wind 55 the clock to run about three hours. Rigidly connected with the winding-arbor of the clock is a pin 14, adapted to engage a stud 15, projecting from a barrel 16, within which is housed a spiral spring 17. On the periphery of this 60 barrel is mounted the spring-contact 5, re-

ferred to in the diagram Fig. 2, which closes a short circuit around the solenoid 2. This contact when the barrel is fully wound bridges two terminals 5^a 5^b for the short circuit. The barrel is latched in this position when set by 70 an offset 18 on the barrel, which is engaged by a spring-detent 19, secured to the casing. Thus it will be seen when the coin locks the handle and movable section of the coin-chute together and the handle is turned the clock is 75 partly wound, and the pin 14, engaging the stud 15, carries the barrel round against the tension of the spiral spring until the lug 18 is latched by the detent 19, at which time the spring-contact 5 will bridge the terminals 5^a 80 5^b. The short circuit is, however, not yet complete, since if left in this condition the consumer might fraudulently use current for any length of time without paying but a single coin. I provide, therefore, a means for 85 preventing the short circuit around the solenoid 2 being closed until the operating-handle has been shifted back partly or wholly toward its initial position, thus insuring the spilling 90 of the coin into the cash-box 9 and disconnecting the operating-handle from the clockwork. This may be simply and effectively accomplished by mounting on the key-stem 12 a movable trailer or bridging-contact 20, adapted to cross-connect two contacts 20^a 20^b, connected in a short circuit around the solenoid 2 when the handle is returned to its initial position. It is evident, therefore, that after operating the clockwork the consumer will have to shift the handle back to its initial position 100 before the extra lights can be used, and until this is effected if more lights than are contracted for are connected in the circuit they can burn only at partial incandescence. On starting the handle, however, on its retrograde movement the pressure on the coin is released and the movable section of the chute having been shifted one hundred and eighty degrees from the position indicated in Fig. 3, the coin drops into the cash-box 9. The 110 movable section of the chute does not return then to its initial position until the clockwork has run down and brought the pin 21 against the fixed stop 22. This section of the chute is then in alinement with the fixed section and 115 a new coin can be deposited and the circuit again closed as before. When, however, this position has been attained, the arm 14 will have reached the position indicated in Fig. 1, forcing open the latch between the lug 18 and the detent 19 and permitting the barrel carrying the contact 5 to obey the impulse of the spiral spring, thereby rapidly snapping 120 open the short circuit and putting the apparatus again under the control of the solenoid 2, which under the increase of current lifts its core and cuts in resistance 4, dimming all the lights. The core of the solenoid carries at its lower end a disk, bridging 125 contacts 3^a 3^b, and I prefer to make these con- 130

tacts yielding, so as to admit a rapid opening of the circuit when the solenoid leaves its core. They may, however, be mounted on journals, as indicated in Fig. 1, and placed side by side, as indicated in Fig. 3, the weight of the core being sufficient under normal strengths of current to strain the control-springs, thus conduced to a rapid opening of the circuit after the core has acquired momentum. Thus it will be seen that if a consumer turns on more than the agreed number of lamps without paying for extra current the lamps will be dimmed, and he will be forced to cut off the extra lamp or put a coin into the prepayment device, by which he can have as much current as he desires.

What I claim as new, and desire to secure by Letters Patent of the United States, is—

1. The combination of a translating circuit on a consumer's premises, a current-limiting switch inaccessible to the consumer to open the same on definite current-flow, and means under the consumer's control for restoring the circuit with increased current-flow in a predetermined way.

2. The combination of a translating circuit on a consumer's premises, a current-limiting switch to open the same on definite current-flow, and means for closing the circuit for a determinate time interval with increased current-flow.

3. The combination with a translating circuit, of a current-limiting switch to open the same on definite current-flow, coin-operated means for closing the circuit irrespectively of the current-flow, and timing mechanism for opening the coin-operated closure.

4. The combination of a consumer's light-

ing-circuit, a current-limiting switch operated at a predetermined current maximum to 40 penalize the customer, and a coin or token operated circuit-closer to permit current to be used above said maximum without penalizing the customer.

5. The combination with a consumer's light- 45 ing-circuit, of a magnet responsive to the current-flow therein, a switch operated by the magnet at definite current value, a resistance cut into circuit to dim the lamps when the switch operates, a short circuit around the 50 magnet, a coin-operated device for closing said short circuit, and timing mechanism for opening the short circuit again after a determinate interval.

6. The combination, with a consumer's circuit, of an automatic switch to cut off the supply at a predetermined current maximum, coin-operated means for insuring a supply at or above said maximum, and a timing device for determining the period of current-flow at 60 or above said maximum.

7. The combination with a consumer's circuit, of an automatic switch for cutting off the supply of current at or above a predetermined maximum, a timing device governing 65 the supply above said maximum, a closed casting, means for winding the timing device, and prepayment mechanism governing said winding means.

In witness whereof I have hereunto set my 70 hand this 29th day of November, 1901.

HARRY W. BROWN.
